PERFORATOR

Filed May 13, 1937

UNITED STATES PATENT OFFICE

2,132,047

PERFORATOR

Edward G. Rix, Chicago, Ill., assignor to American Perforator Company, Chicago, Ill., a corporation of Illinois

Application May 13, 1937, Serial No. 142,325

5 Claims. (Cl. 164—93)

My invention relates to perforators.

One of the objects of my invention is to provide a perforator having improved actuating means for the punch-carrying slide.

5 A further object of my invention is to provide an improved perforator in which the lower punch guide which serves as a stripper plate is fitted with a head so that it will locate the stripper plate to bring the holes into alignment with the 10 punches and with the holes in the die plate.

A further object of my invention is to provide an improved perforator in which the head is provided with guides for the pusher bar and with wells or recesses to receive the lever 15 turning spring and the bumper for the lever.

A further object of my invention is to provide a perforator in which stop links are provided to limit the upward movement of the lever.

A further object is to provide an improved 20 perforator in which the lever pivoted on the head actuates the pusher bar and is provided with stop links, and means for holding the upper end of the returning spring in place.

A further object of my invention is to provide 25 an improved perforator having aligned holes in the spring well and lever for receiving a packing screw.

A further object of my invention is to provide 30 an improved perforator having aligning openings in the stripper plate and die to hold these parts in their proper relative position when drilling the holes in the die plates.

A further object of my invention is to provide 35 a perforator construction which can be used in building up perforators having different depths of throat, simply by changing the plate brackets and base.

Further objects and advantages of the invention will appear from the description and claims.

40 In the drawing, in which is shown an embodiment of my invention,

Figure 1 is a side elevation of a perforator;

Fig. 2 is a section substantially on the line 2—2 of Fig. 3;

45 Fig. 3 is a section substantially on the line 3—3 of Fig. 2;

Fig. 4 is a horizontal section on the line 4—4 of Fig. 2 and showing also in plan the bumper which is above the line 4—4;

50 Fig. 5 is a detail showing the stripper plate and die plate; and

Fig. 6 is a side elevational view of the stripper plate and die plate assembled in position for drilling the holes in the die plate.

55 Referring to the drawing in detail, the perfora-

rator shown comprises a base 1 which may be of cast metal, a pair of parallel spaced plate brackets 2 mounted on the rear end of the base and having portions overhanging the base to provide a throat between the base and brackets, 5 a head 3 which may be a die casting extending between said plate brackets and supported thereby, a punch-actuating slide or pusher 4 extending between said side plates and having its ends slidably mounted in vertically extending guide 10 channels 5 in the side plates 6 forming part of the head 3, an actuating lever 7 for the punch-actuating member 4 pivotally mounted at 8 on the head 3 adjacent the front end thereof and extending rearwardly from its pivotal axis, a 15 coil compression spring 8a for returning the lever 7, a pair of links 9 pivotally connected at 10 with the lever 7 and at 11 with the ends of the punch-actuating member 4, a punch guiding and stripper plate member 12 below the punch- 20 actuating member 4, and a die plate 13 below the stripper plate 12 and riveted to the base 1 at 14.

The base 1 is provided with a pair of upwardly extending standards 15 at its rear end to which the plate brackets 2 may be secured by rivets 16, 25 or the like. The head 3 provided with the pair of side plates 6 lying against the plate brackets 2 may be secured thereto in any suitable manner, as by rivets 17. The front end of the head 3 is recessed as indicated at 18 to receive the front 30 ends of the plate brackets 2. The front end of the head is also provided with a pair of horizontally extending recesses 19 to receive and position a pair of parallel horizontal tongues 20 on the guiding and stripper member 12, as 35 shown in Fig. 1.

The spring well 21 which receives the lower end of the spring 8a is supported by and between the side plates 6 of the head by means of webs 22, as shown in Figs. 2 and 4. The bumper-receiving pocket 23 is also supported by and between the side plates 6 of the head by means of webs 24.

A pair of links 25 are provided for limiting the upward movement of the lever 7, these links 45 being pivotally connected with down-turned portions of the lever, as indicated at 26. The links are slotted at 27 to receive a screw 28 which extends through the tongues 20, plate brackets 2, and side plates 6, as shown in Figs. 2 and 4. 50

The punch-actuating member 4 comprises a pusher member 29 which may be a die casting pivotally connected with the actuated links 9 at 11 and a channel member 30 which may be of sheet metal secured to the pusher member by 55

means of rivets 31 or the like. The heads of the punches 32 are held between the pusher member and the channeled lifter member as shown in Fig. 2. The lower ends of the punches are guided 5 in the stripper plate 12 so as to pass through the openings in the die plate 13 when the lever 7 is depressed.

In the manufacture of the stripper plate and die plate, the punch openings in the stripper plate 12 may be die-cast. The stripper plate 12 and die plate 13 are then assembled in proper relation by means of positioning pins 33 passing through registering openings in the stripper plate and die plate, as shown in Fig. 6. The 10 punch openings in the die plate 13 may then be drilled, using the openings in the stripper plate as guide openings for the drills. The positioning pins 33 may then be removed and when the stripper plate and die plate are assembled in the 15 perforator, the openings will be properly positioned so that the stripper plate openings will align with the die plate openings.

The lower end of the lever returning spring 8a is positioned in the spring well 21 and the upper 20 end is positioned by the downwardly-punched circular flange 34 in the actuating lever which extends into the upper end of the lever-returning spring. The lower end of the spring well is provided with an opening 35 which is in alignment 25 with the opening formed by the flange 34 in the lever when the lever is depressed, so that in packing the perforator for shipment, a screw can be inserted through these openings and a nut threaded into the ends of the screw to hold the 30 lever in its lowered position.

Further modifications will be apparent to those skilled in the art and it is desired, therefore, that the invention be limited only by the prior art and the scope of the appended claims.

Having thus described my invention, what I claim and desire to secure by Letters Patent is:

1. A perforator comprising a base, a pair of parallel spaced plate brackets mounted on the rear end of said base and having portions overhanging said base to provide a throat between the base and brackets, a head extending between said plate brackets and supported thereby, said head comprising a pair of parallel spaced side plates extending along and secured to said 45 plate brackets, each side plate having a vertically-extending guide channel therein adjacent its front end, a punch-actuating member extending between said side plates and having its ends slidably mounted in said channels, an actuating lever for said punch-actuating member pivotally mounted on said head adjacent the front end thereof and extending rearwardly from its pivotal axis, and a pair of links pivotally connecting said lever with the ends of said punch-actuating 50 member.

2. A perforator comprising a base, a pair of parallel spaced plate brackets mounted on the rear end of said base and having portions overhanging said base to provide a throat between the base and brackets, a head extending between said plate brackets and supported thereby, said head comprising a pair of parallel spaced side plates extending along and secured to said plate brackets, each side plate having a vertically-extending guide channel therein adjacent its front end, a punch-actuating member extending between said side plates and having its ends slidably mounted in said channels, an actuating 65 lever for said punch-actuating member pivotally

mounted on said head adjacent the front end thereof and extending rearwardly from its pivotal axis, a pair of links pivotally connecting said lever with the ends of said punch-actuating member, and a punch guiding and stripper plate member 5 below said punch-actuating member, said guiding and stripper member having a pair of parallel horizontal tongues embracing said head, said head having a pair of horizontally-extending recesses to receive and position said tongues.

3. A perforator comprising a base, a pair of parallel spaced plate brackets mounted on the rear end of said base and having portions overhanging said base to provide a throat between the base and brackets, a head extending between said plate brackets and supported thereby, said head comprising a pair of parallel spaced side plates extending along and secured to said plate brackets, each side plate having a vertically-extending guide channel therein adjacent its front end, a punch-actuating member extending between said side plates and having its ends slidably mounted in said channels, an actuating lever for said punch-actuating member pivotally mounted on said head adjacent the front end 10 thereof and extending rearwardly from its pivotal axis, and a pair of links pivotally connecting said lever with the ends of said punch-actuating member, said head having a spring well supported by and between said side plates, and a coil spring having its lower end supported in said well and its upper end acting on said lever, said head also having a bumper pocket supported by and between said side plates, and a bumper mounted in said pocket for engaging said lever 15 to limit its downward movement.

4. A perforator comprising a base, a pair of parallel spaced plate brackets mounted on the rear end of said base and having portions overhanging said base to provide a throat between the base and brackets, a head extending between said plate brackets and supported thereby, said head comprising a pair of parallel spaced side plates extending along and secured to said plate brackets, each side plate having a vertically-extending guide channel therein adjacent its front end, a punch-actuating member extending between said side plates and having its ends slidably mounted in said channels, an actuating lever for said punch-actuating member pivotally mounted on said head adjacent the front end thereof and extending rearwardly from its pivotal axis, a pair of links pivotally connecting said lever with the ends of said punch-actuating member, and a coil compression spring for raising 30 said lever, said lever being of sheet material having its opposite longitudinal edges turned downwardly to provide pivotal connections for said links and having a depressed portion extending inside the upper end of said coil spring 35 for centering it.

5. A perforator construction comprising a punch guiding and stripper plate member having a plurality of punch-receiving holes therethrough, and a die plate having a plurality of punch-receiving openings in alignment with the punch-receiving openings of the stripper plate, said stripper plate and die plate having a plurality of registering openings therein to receive positioning pins for holding the guiding and stripper plate and the die plate in definite relative positions, whereby the stripper plate openings can be used as guides in drilling the openings in the die plate.
